FOLDING STAIRS

George Mattis, Oakland, and Stanley Rapp, Menlo Park, Calif.; said Rapp assignor to said Mattis

Application December 29, 1952, Serial No. 328,282

4 Claims. (Cl. 228—30)

The present invention relates to an improvement in folding stairs and in particular to foldable stairs adapted for mounting upon a vertical wall.

Many modern living and working quarters have a limited space and it is common in such circumstances to provide overhead or raised storage facilities. It is quite inconvenient to have to employ a chair or a conventional ladder to reach such raised facilities and the present invention provides improved folding stairs adapted for permanent mounting below the raised storage or other facilities. Not only does the present invention provide a sturdy readily available stairway but in addition the stairway so provided is adapted in folded or retracted position to occupy a minimum of space and further to readily fit into the surroundings so as to be substantially indistinguishable as stairs. The stairway is particularly adapted for disposition within a rectangular recess or depression in a vertical wall and when folded therein assumes the appearance of a row of drawers so as to blend into the surroundings.

It is accordingly an object of the present invention to provide improved folding stairs.

It is another object of the present invention to provide improved folding stairs adapted for mounting within a depression in a vertical wall and retractable into closing relation thereto.

It is a further object of the present invention to provide an improved folding stairway adapted for convenient mounting upon a vertical wall and providing maximum rigidity in unfolded position.

It is still another object of the present invention to provide a folding stairway having an improved folding and supporting mechanism.

It is still a further object of the present invention to provide an improved folding stairway adapted for permanent mounting within a recess in a vertical wall and folding very compactly to fit into a very shallow recess.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

The invention is disclosed with respect to a single preferred embodiment illustrated in the attached drawing wherein:

Figure 1 is a side elevational view of the stairs in position of use.

Figure 2 is a side elevational view of the stairs in retracted or folded position.

Figure 3 is a front elevational view of the stairs retracted.

Figure 4 is a front elevational view of the stairs unfolded in position of use.

Figure 5 is a partial plan view of the stairs in retracted position.

2

Figure 6 is a plan view of the improved folding stairs with an alternative closure means.

Figure 7 is a plan view of an alternative embodiment of the improved folding stairs, and

Figure 8 is an elevational view of the embodiment of Figure 7.

Considering now the structure of the embodiment of the invention illustrated in Figures 1-5 and viewing the stairs in unfolded position, there will be seen from Figure

10 1 to be provided a number of flat rigid plates 11, 12, and 13 which are adapted to serve as stair treads. With the stairs unfolded plates 11-13 are oriented in parallel relationship, vertically spaced, and horizontally offset in proper disposition for convenient walking thereon as a 15 conventional fixed stairway. Upper plate 11 is provided with a pair of rigid extensions 14 connected one to each of the rear corners of plate 11 and extending back therefrom.

The improved folding stairs of the present invention are 20 designed for mounting upon a vertical wall 16 and are particularly adapted for mounting within a shallow rectangular recess or depression therein. Thus the extensions 14 of upper plate 11 have pivotal connections 18 at the ends thereof engaging the vertical side walls of depression 17 so that plate 11 is pivotable into and out of depression 17. Plates 11-13 are joined together by a plurality of straight rigid spacing bars and these bars may be considered as comprising two sets of bars with each set including a long front bar 21 and a short rear bar 22. Front bar 21 is pivotally connected to the sides of plates 11-13 adjacent the front corners thereof and extends below lower plate 13 when the stairs are in operated position to contact the floor 23 from which the stairs extend. The lower end of front bar 21 is preferably 25 capped with or formed of a resilient material 24, such as rubber, in order to grip floor 23 and to prevent gouging thereof. For the mounting of rear bar 22 plates 12 and 13 are each provided with a pair of raised or upstanding mounting members 26 and 27 attached to the rear corners 30 of plates 12 and 13 respectively. Bar 22 is pivotally connected to mounting members 26 and 27 of plates 12 and 13 and to the extension 14 of plate 11 a like distance above plate 11 so that rear bar 22 is disposed parallel to front bar 21 and both pivotally engage plates 11-13 adjacent aligned corners thereof. The combination of each set of bars 21 and 22 and plates 11-13 comprise a foldable or pivotable parallelogram with the two parallelograms being interconnected by plates 11-13. These parallelograms are pivotable upwardly from the above noted 35 operated position with plates 11-13 disposed in offset parallelism and bars 21 and 22 being disposed at a slant interconnecting plates 11-13 to a folded or retracted position with plates 11-13 in vertical planar alignment and bars 21 and 22 vertically disposed.

45 55 In addition to the above-noted support or mounting of the stairs by extensions 14 of upper plate 11 there are provided further support means adapted to more firmly anchor the stairs in position. These support means include a pair of foldable links 28 each of which includes

two straight rigid elements 31 and 32 of substantially the same length pivotally connected together at the ends thereof. One end of each link 28 has a pivotal connection 33 therein which is adapted to engage a vertical side of depression 17 in wall 16 and there is provided a

60 pair of raised mounting members 34 on the corners of upper plate 11 to which the other end of links 28 are pivotally attached. Links 28 are made with sufficient length so that in the operated position of the stairs the links are fully extended or unfolded and the pivotal

65 70 connections 33 at the ends thereof are preferably so disposed within depression 17 that links 28 are substantially aligned with front bars 21 when the stairs are in operated

position in order to provide maximum support therefor. A further support member may be provided in the form of a pair of braces 36 which are pivotally connected at 52 one to each of the rear bars 22 below upper plate 11 and which extend downward and back therefrom. Braces 36 are each provided with a pivotal connection 37 at the end thereof which is adapted to engage a vertical side wall of depression 17 and braces 36 may be bent at 36' in an obtuse angle in order that they will not touch the mounting members 26 of intermediate plate 12 when the stairs are in folded or retracted position.

The support members of the stairway provide rigidity to the stairs when same is in unfolded operated position and in this position links 28 are placed in tension and braces 36 are placed in compression. In order that 15 the stairs may be folded into the above described retracted position the pivotal connections 18, 33, and 37 of support members 14, 28 and 36 are adapted for mounting in vertical alignment within wall recess 17, however, the vertical spacing of these connections is dependent 20 upon the relative dimensions of the stair elements.

As above noted plates 11-13 are adapted to serve as stair treads and thus the upper surfaces thereof in operated position of the stairway may be roughened to provide improved safety, if so desired. The dimensions 25 of the stairs is related to the dimensions of recess 17 in wall 16 so that the stairs are adapted to retract entirely within recess 17. To this end plates 11-13 are formed with a width substantially equal to the width of recess 17, there being allowed a slight leeway on each side of 30 plates 11-13 to accommodate bars 21 and 22 which may be made quite thin to minimize the necessary difference in width of plates 11-13 and recess 17. Also the summation of the depths of plates 11-13 is made substantially equal to the height of recess 17 so that in retracted position the plates 11-13 in vertical planar alignment substantially close recess 17. Further concealment of the stairs may be accomplished by finishing the under surfaces of plates 11-13 in the manner of drawer fronts and attaching drawer pulls 39 thereto so that in retracted position the stairs are indistinguishable from a set of drawers in wall 16. These drawer pulls 39 also function as handles for convenient unfolding of the stairs from retracted position. In some circumstances it is desirable to even further conceal the nature of the stairs and for this purpose there may be provided a pair of covering strips 41 which are vertically disposed along the sides of recess 17 overlaying a portion of same and are pivotally mounted therat to freely swing about a vertical axis. These strips 41 are preferably spring mounted at 41' to assume a normal position extending over the vertical edges of recess 17 and thus in retracted position of the stairs extend over the vertical edges of plates 11-13 to cover and conceal bars 21 and 22 and pivot outwardly when the stairs are unfolded to extend outwardly from wall 16 alongside the stairs while returning of their own accord to normal position when the stairs are retracted.

It will be appreciated that the above-described embodiment of the invention is so constituted as to have maximum rigidity in operated position and that certain of the stair elements may be modified or even eliminated if so desired but with a loss of rigidity. Thus where only normal loads are to be placed on the stairs bar 21 may be made the same length as bar 22 with the lower portion of bar 21 removed so that it does not contact the floor, there being provided by support members 14, 28, and 36 sufficient strength for the stairs to support normal loads. There may also be provided one or more catch mechanisms 42 for the purpose of retaining the stairs in retracted position and such mechanism may include a pin 43 upon upper step 11 and a spring clip 44 mounted within recess 17 in position to engage pin 43 when the stairs are retracted. This function may, however, be accomplished by cover strips 41 when same are spring loaded.

Although the present invention is particularly adapted for construction in the above-noted manner to present the appearance of drawers in retracted position it is not so limited and various other closure means may be provided and in fact certain other mounting means are also possible. Thus, recess 17 may be closed by a door to simulate a cupboard or the like and in this respect reference is made to Figure 6 showing in plan view such an arrangement. The stairs are mounted as before within recess 17, however, covering strips 41 are not provided and instead a door 46 is mounted by hinges 47 upon the wall 16 adjacent recess 17. Door 46 is adapted to swing upon hinges 47 from a position in closing relation to recess 17 to a position such as shown in Figure 6 wherein the stairs may be unfolded, as shown. Suitable handles and door catch mechanism may be provided as desired.

Considering a further manner of mounting the invention it is noted that it may under certain circumstances be advantageous to displace the stairs or to provide for disposing them in some other relation to the vertical wall 16 when they are unfolded and in this respect reference is made to Figures 7 and 8 showing a modification of the invention having such capabilities. The recess 17 in wall 16 is adapted for closure by door 46 which is mounted by hinges 47 so as to be pivotable about one vertical edge of recess 17 as in Figure 6. In this instance, however, the improved folding stairs are mounted upon door 46 so that they too pivot out of recess 17 when door 46 is opened and the stairs may thus be disposed at any desired angle to wall 16. As shown in Figure 7 the door and attached stairs have been pivoted 180 degrees so that the stairs are disposed normal to wall 16 but displaced from recess 17 and it is noted that the back wall of recess 17 may be either eliminated or be made movable under the circumstance that access is desired to the space behind the wall 16, as for example, when wall 16 is the front of a cabinet or counter. To facilitate the mounting of the stairs upon door 46 there is provided a pair of vertical door sides 48 rigidly attached to the back portion of door 46 and extending normal thereto for disposition within recess 17 when door 46 is closed. Inasmuch as the stairs are mounted upon a hinged door it is advantageous to provide means for supporting the stairs other than the door hinge and thus the stairs are modified in this respect. The stairs may include three stair treads 11-13 connected by front bars 21 and rear bars 22 pivotally engaging treads 11-13, however, the extensions 14 of upper tread 11 are modified to comprise extensions 14a which are somewhat larger and extend upward as well as back from upper tread 11. Extensions 14a are pivotally connected at their back ends to door sides 48 and there is provided a pair of braces 36 pivotally connected to bars 22 between treads 11 and 12 and to door sides 48. The upper support means of the previously described embodiment is replaced by a pair of vertical legs 49 which are pivotally connected at their upper ends to tread extensions 14a slightly forward of the back corners thereof. Legs 49 extend vertically downward from the pivotal top mounting into engagement with the floor 23 in bearing relation thereto and are pivotally connected to braces 36. Legs 49 thus provide support for the stairs and take the place of foldable links 28 which depended from wall 16 and legs 49 brace the stairs from the floor to support the stairs substantially independent of door 46 so as not to strain hinges 47 thereof.

Folding of the stairs is accomplished in the same manner as described in connection with the embodiment of Figure 1 and with regard to legs 49 there are provided a pair of slots 51 in upper tread 11 adjacent extensions 14a thereof and extending therewith to the back edge of tread 11. Legs 49 extend through these slots 51 on the inner sides of extensions 14a and when the stairs are folded legs 49 swing back through these slots into hanging position parallel and adjacent the vertically aligned treads 11-13. Slots 53 are formed in legs 49 so that the pivotal connection 54 to braces 36 are also slidable to allow folding of

those elements when the stairs are retracted. Suitable means may be provided to hold the stairs in folded position upon door 46 and to swing the stairs between folded and unfolded position, such as shown in Figures 1-5 and here eliminated for simplicity of illustration and description.

It will be appreciated from the foregoing that the improved folding stairs of the present invention are not only particularly rigid and safe as well as being readily movable between unfolded and retracted position but that they are quite compact and occupy a very small space in folded position, thus being very well adapted for use where space is at a premium. As various embodiments and numerous modifications thereof are possible within the scope of the invention attention is invited to the following claims for a precise definition of the invention.

What is claimed is:

1. Improved folding stairs adapted for mounting within a shallow rectangular recess in a vertical wall and comprising two pairs of parallel bars, a plurality of rigid plates each having one surface thereof comprising stair treads pivotally mounted on said pairs of bars and spaced apart equal distances along said bars to form a movable parallelogram pivotal between a retracted position with said plates in vertical planar alignment and an operated position with said plates in parallel spaced disposition, the uppermost of said plates having a pair of extensions thereon for pivotal mounting within the recess in said wall, a pair of foldable links pivotally mounted upon the front corners of said uppermost plate and adapted for pivotal connection at the opposite ends thereof within the recess in said wall above said extensions, and a pair of braces pivotally joined to one pair of said bars and extending downwardly therefrom for pivotal mounting within the recess in said wall below said extensions whereby said stairs are retractable into the recess in said wall and rotatably movable therefrom into operated position providing a rigid stairway, and said plates having a length parallel to said wall substantially equal to the width of the recess therein and a combined width equal to the height of said wall recess whereby said plates close said wall recess in retracted position.

2. An improved folding stairs as claimed in claim 1 further defined by a pair of cover plates adapted for pivotal mounting upon said vertical wall one on each side of the recess therein and extending thereover whereby same are movable from an open position with said stairs in operated position to a closed position with said stairs in retracted position to cover the vertical edges of said stairs in retracted position.

3. Improved folding stairs comprising a plurality of aligned flat rigid plates having one side thereof adapted as stair treads and the opposite side thereof adapted to carry handles, said plates having at the rear corners thereof of raised mounting members, a first pair of parallel bars each pivotally engaging aligned mounting members upon said plates, a second pair of parallel bars pivotally engaging the edges of said plates adjacent aligned corners thereof whereby said plates are pivotable from a first position in vertical planar alignment to a second position with said plates in offset spaced parallelism, a pair of rigid extensions attached to the mounting members of the uppermost of said plates and extending from said plate with pivotal connections at the end thereof, a pair 15 of foldable links each pivotally connected to a front corner of the uppermost of said plates and extending therefrom, said links having pivotal connections at the ends thereof adapted for vertical alignment with the connections at the ends of said extensions, and a pair of 20 braces each pivotally engaging one of said bars below the connection thereof to a mounting member of the uppermost of said plates and said braces being adapted to extend downwardly therefrom with a pivotal connection at the end thereof adapted for vertical alignment with 25 the pivotal connections at the ends of said extensions whereby said stairs are adapted for mounting within a recess in a vertical wall and is there movable from said first position folded within said recess to said second position with said plates disposed as stair treads.
- 30 4. Improved foldable stairs as claimed in claim 3 further defined by said plates having a width substantially equal to the width of the recess in the wall upon which the stairs are mounted and a combined depth substantially equal to the height of said recess whereby said stairs 35 in said first folded position disposes said plates in closing relation to said recess.
